UNITED STATES PATENT OFFICE.

ABRAHAM I. LEWIS, OF NEWARK, NEW JERSEY.

ORNAMENTAL BUTTON.

Application filed May 26, 1925. Serial No. 33,014.

To all whom it may concern:

Be it known that I, ABRAHAM I. LEWIS, a citizen of the United States, and a resident of Newark, in the county of Essex and State of New Jersey, have invented a new and Improved Ornamental Button, of which the following is a full, clear, and exact description.

This invention relates to ornamental buttons for garments and for other purposes where an ornamental member is desired, the object being to provide a construction which will disclose a button structure with a stone or other ornament thereon while at the same time presenting means for readily connecting the button structure by stitches to the garment.

Another object of the invention is to provide an ornamental button wherein a socket is provided which is adapted to receive threads in order to connect the button to a garment and also will act to receive an ornament.

A further object of the invention is to provide an ornamental button wherein means are provided for supporting a jewel on the button and also means are provided for receiving a stitching in such a manner that the same cannot be seen from the exposed face of the button.

In the accompanying drawing—

Figure 1 is a plan view of the button, disclosing an embodiment of the invention.

Figure 2 is a rear view of the button shown in Figure 1.

Figure 3 is a sectional view through Figure 1 on line 3—3, part of a garment being shown in connection therewith.

Figure 4 is an elevation of an article of wearing apparel with several buttons embodying the invention applied thereto for illustrating their appearance when in use.

Referring to the accompanying drawing by numerals, 1 indicates the body of the button which may be of any desired kind, as for instance, what is commonly known as a pearl button. This button is provided with an aperture 2 in which a socket member 3 is mounted, the same being normally known as a socket. This socket member is provided with either a prong or an annular structure 4 acting to hold the stone 5 in place. Heretofore, structures of the kind just described have been provided but in order to connect the button 1 to a garment, apertures were required in the button in order that the

stitching thread may hold the button in place. In the present invention, however, a pair of inwardly extending members 6 project from the body of the socket, said members being connected by the bar 7. Also clamping members 8 and 9 extend from the socket 3, which clamping members act to clamp the socket firmly to the button 1. In forming these members, preferably a blank 65 is provided with a tubular extension extending from the bottom and this tubular extension is closed at the end so that when it is cut at two points the members 8 and 9 may be bent in opposite directions and the 70 central portion may remain as the members 6 and 7. After the parts have been assembled as shown in Figures 1 and 2, the completed button may be stitched onto the garment 10 by suitable stitching 11. It will be noted that the stitching 11 cannot be seen 75 from the front face of the button but an ample amount of thread may be used for securely connecting the button to the garment.

As indicated in Figure 4, a certain form of wearing apparel is shown with four buttons thereon but it will be evident that the buttons may be used on any form of garment and also any number may be used and grouped in any desired manner. In addition to presenting merely ornamental structures as shown in Figure 4, the buttons could be used for useful purposes and in connection with buttonholes. When viewed from the front as shown in Figure 4, the stitching 11 cannot be seen and, consequently, a very pleasing appearance is given to the button.

What I claim is:

1. An ornamental button for garments, comprising a button body, a socket formed in said body and a jewel mounted in part of said body, said socket being provided with clamping members whereby the same is 100 clamped to said button body, and a bar arranged opposite the jewel, said bar being adapted to receive threads when the button is sewed in place on a garment.

2. An ornamental button, comprising a 105 button body, and means carried by the button body acting to hold a stone on one face of the body and presenting a thread receiving bar on the opposite side.

3. An ornamental button, comprising a 110 button body formed with an aperture and a socket fitted into said aperture, said socket

being formed with means on one end for receiving a stone, and a plurality of members on the opposite end, certain of said members acting to clamp a socket to said button body, the other of said members presenting a thread receiving structure whereby the button may be sewed to a garment.

4. An ornamental button, comprising a button body, a jewel mounted on one face of

the body, and a thread receiving bar mounted on the opposite face of the body.

5. An ornamental button, comprising a button body, means carried by the body extending therethrough, said means supporting a jewel on one face of the button, and a bar on the opposite face of the button, said bar being spaced away from the button.

ABRAHAM I. LEWIS.
